United States Patent Office.

JOHN L. DAWES, OF PITTSBURG, PENNSYLVANIA.

Design No. 4,789, dated April 11, 1871.

DESIGN FOR A BITTER-TUBE.

The Schedule referred to in these Letters Patent and making part of the same.

To all whom it may concern:

Be it known that I, JOHN L. DAWES, of Pittsburgh, in the county of Allegheny and State of Pennsylvania, have invented a new and useful Improved Design for Bitter-Tube; and I do hereby declare the following to be a full, clear, and exact description thereof, reference being had to the accompanying drawings making a part of this specification, in which—

Figure 1 is a side, and

Figure 2 is a sectional view of the bitter-tube, and illustrative of my improved design.

Like letters of reference indicate like parts in each.

The bitter-tube shown is designed more particularly for use with bottles containing or designed to contain bitters, table-sauces, fluid extracts, catsup, vinegar, and other like fluids, which are designed for use in comparatively small quantities.

c is the tube.

b, the cork.

a, a flanged cap covering it.

s', a fastening-wire passing through an elongated eye or loop in the lower end of the stems *s*, to the upper end of which latter is fastened a double conical plug, *e*. The stem *s* has a little longitudinal play, so that the plug *e* can rise from and fall onto its seat.

I am aware that stoppers for large-mouthed bottles have been made on the same mechanical principles as those involved in the design described; hence I limit my design to the conformation of the small tube and plug, suitable for table-sauce and other bottles of like use.

What I claim as my improved design, and desire to secure by Letters Patent, is—

The design for bitter-tube, substantially as shown.

In testimony whereof I, the said JOHN L. DAWES, have hereunto set my hand.

JOHN L. DAWES.
